United States Patent Office

Des. 181,112
Patented Oct. 1, 1957

181,112

VENDING STAND ENCLOSURE

Harvey J. Smith, Greensboro, N. C.

Application April 4, 1956, Serial No. 40,902

Term of patent 14 years

(Cl. D52—3)

FIG. 1

FIG. 2

FIG. 3.

FIG. 4.

Figure 1 is a front perspective view of a vending stand enclosure in open position, showing my new design;

Figure 2 is a perspective view of the enclosure of Figure 1, illustrating the enclosure front in a closed position;

Figure 3 is a rear perspective view of the vending stand enclosure of Figure 1; and

Figure 4 is a side elevational view of the enclosure in the open position of Figure 1.

The broken outline forms in Figure 1 represent vending machines and are shown for illustrative purposes only.

What is claimed is:

The ornamental design for a vending stand enclosure, as shown and described.
